US00D479131S

(12) United States Design Patent (10) Patent No.: US D479,131 S
 Warner et al. (45) Date of Patent:  Sep. 2, 2003

(54) BOTTLE

(75) Inventors: Jim Warner, Hoboken, NJ (US);
Martin Short, Brooklyn, NY (US);
Cynthia A. Headen, Newtown, CT (US)

(73) Assignee: PepsiCo, Inc., Purchase, NY (US)

() Term: 14 Years

(21) Appl. No.: 29/153,469

(22) Filed: Jan. 8, 2002

(51) LOC (7) Cl. 09-01

(52) U.S. Cl. D9/538; D9/539; D9/552;
 D9/558
